UNITED STATES PATENT OFFICE.

FRANK P. DOOLEY, OF CHICAGO, ILLINOIS.

DESIGN FOR A METAL FABRIC.

53,238.

Specification for Design.

Patented Apr. 29, 1919.

Application filed March 4, 1918. Serial No. 220,130. Term of patent 14 years.

To all whom it may concern:

Be it known that I, FRANK P. DOOLEY, a citizen of the United States, residing at Chicago, in the county of Cook and State of Illinois, have invented a new, original, and ornamental Design for a Metal Fabric, of which the following is a specification, reference being had to the accompanying drawings, forming part thereof.

Figure 1 is a plan view of the fabric showing my new design and Fig. 2 is a side view.

I claim:

The ornamental design for a metal fabric, as shown.

FRANK P. DOOLEY.
